CARBURETOR

William F. Ott, St. Louis County, Mo., assignor to ACF
Industries, Incorporated, New York, N.Y., a corpora-
tion of New Jersey

Filed May 9, 1960, Ser. No. 60,510

Term of patent 14 years

(Cl. D77—1)

FIG. 1.

Des. 190,264

PAGE 2

FIG. 2.

FIG. 3.

FIG. 4.

FIG. 5.

Fig. 1 is a top plan view of a carburetor, showing my new design.

Fig. 2 is a side elevation thereof.

Fig. 3 is an elevation thereof as seen from the opposite side of Fig. 2.

Fig. 4 is an end elevation thereof as seen from the right of Fig. 3.

Fig. 5 is an end elevation thereof as seen from the left of Fig. 3.

I claim:

The ornamental design for a carburetor, as shown.
